United States Patent

Des. 242,395
Patented Nov. 16, 1976

242,395

KEY RING

Samuel J. Bellin, Cranston, R.I., assignor to
Crownmark Corporation

Filed June 9, 1975, Ser. No. 585,333

Term of patent 14 years

Int. Cl. D3—01

U.S. Cl. D87—8

FIG. 1

FIG. 2

FIG. 3

FIG. 4

FIG. 1 is a front elevational view of a key ring showing my new design, the rear elevational view being substantially a mirror image thereof;

FIG. 2 is an end elevational view thereof;

FIG. 3 is a top plan view thereof; and

FIG. 4 is a bottom plan view thereof.

I claim:

The ornamental design for a key ring, substantially as shown and described.
